A. E. SMITH.
CARRIAGE AXLE.

No. 96,043.

Patented Oct. 19, 1869.

Alfred E. Smith

United States Patent Office.

ALFRED E. SMITH, OF BRONXVILLE, NEW YORK.

Letters Patent No. 96,043, dated October 19, 1869.

IMPROVEMENT IN CARRIAGE-AXLES.

The Schedule referred to in these Letters Patent and making part of the same.

To all whom it may concern:

Be it known that I, ALFRED E. SMITH, of Bronxville, Westchester county, and State of New York, have invented certain new and useful Improvements in the Manufacture of Axles, in combination with case-hardened malleable-iron collars or ferrules, as bearing-surfaces for the axle to run on, for use of wagons and other vehicles; and I do hereby declare that the following is a full and clear description of the same.

The first object of my invention is to make an axle of steel, (though good wrought-iron may answer,) for the purpose of obtaining lightness with strength.

As toughness of metal is the main requisite of an axle, it follows, as a matter of course, that the metal must be left untempered and soft, and consequently soon wears untrue in a case-hardened metal box, because the wear on an axle is constant, and always on the lower side of it. Therefore,

The second object of my invention is to make an axle with case-hardened bearing-surfaces in combination therewith, and thus obtain the strength and toughness of steel axles, with the hardness of the highest-tempered metal, as a wearing-surface, to give strength and durability of wear to the axle; and

The nature of my invention consists in combining, with the spindle of an axle, case-hardened malleable cast-iron ferrules, for the purpose of forming a compound axle, for wagons and other vehicles, composed of tough untempered metal, and case-hardened iron, malleable metal, whereby a great improvement is obtained over all other axles, for like purposes, ever before made.

But, to describe my invention more particularly, I will refer to the accompanying drawings, forming a part of this specification, the same letters of reference, wherever they occur, referring to like parts.

Figure 1 is a side view of the spindle of an axle, showing the ferrules secured thereon.

Figure 2 is a cut section of the same.

Figures 3 and 4 are a side and end view of the ferrule on the end of the spindle.

Figures 5 and 6 are a side and end view of the ferrule on the heel of the spindle.

Letter A represents the body of the axle, and B, the spindle, on which the wheel rotates.

This axle is made of steel, which is preferred to wrought-iron, because of its greater strength to an equal weight of metal, and therefore is an indispensable desideratum in all light and fancy wagons and carriages.

To prevent its wearing out, and, at the same time,

to strengthen it, ferrules of case-hardened malleable iron, C and D, are fitted upon the heel and point of the spindle.

That on the heel is secured from coming off by driving up a shoulder of metal, E, on the spindle, against the end of the ferrule C, while that on the point of the spindle is, in a like manner, prevented from coming off by driving up the end of the spindle against it, though, practically, this is not material, as the nut will always keep it from coming off.

These ferrules form the bearings in the box in the hub of the wheel, and, as they are case-hardened, will endure for a long time before showing the least wear on their lower sides, and when they do happen to exhibit any such defect, the ferrules may, by means of a sharp bite with a monkey-wrench, be rotated on the spindle far enough to present a new wearing-surface, and thus restore the axle to its original perfection of wearing-qualities.

It will be obvious, also, that the ferrule at the heel of the spindle, being an independent piece of metal from that of the spindle which it surrounds, acts like a hoop or reinforce to support and strengthen the spindle at its weakest point, as, of course, it is known to all, in any way conversant with the use of wagons, or other vehicles, that the spindle never breaks at any other point except at the heel; therefore, independent of the ferrule as forming a case-hardened bearing for the wheel to run on, it has the other equally-important merit of adding strength to the axle.

It will be obvious, also, that the space between the ends of the ferrules admits of an abundant application of lubricating-material, to keep the bearings at all times well oiled.

I am aware that untempered bands of steel have been shrunk on the spindles of axles; but as the mere application of bands to the spindle is not the object of my invention, which is for the special purpose of making a malleable-iron case-hardened bearing-surface, which is not practicable with steel bands, if heated and shrunk on the axle, therefore, I disclaim the use of steel bands on the spindles of axles of wagons, and other vehicles; but

What I do claim, is—

The combination of the case-hardened malleable-iron ferrules, C and D, with and secured upon the spindle B, substantially as described, made and operating substantially as hereinbefore set forth.

ALFRED E. SMITH.
